SEWING CHEST

Filed March 10, 1931

T19.2.

JOHN E. MULREY
INVENTOR

BY *Victor J. Evans & Co.*
ATTORNEY

WITNESS:
John Frank

UNITED STATES PATENT OFFICE

JOHN E. MULREY, OF TRENTON, NEW JERSEY

SEWING CHEST

Application filed March 10, 1931. Serial No. 521,604.

This invention relates to sewing chests and it has for one of its objects the provision of convenient, efficient and novel article-holding means.

Another object of the invention is the provision of a novel retaining means for sharp pointed articles such as pins, needles, and so forth.

Other objects will be appreciated from reading the following specification.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Fig. 1 is a perspective view, partly broken away, of the sewing chest in open position, the lower part only of the cover being shown.

Fig. 2 is a vertical transverse section of the closed chest taken on the center line of the spindle and trunnion.

Referring to the drawings for a more detailed description thereof, the numeral 5 indicates the chest having a body portion 6 and a deep cover 7, the latter being connected to the body by means of hinges 8. Cork blocks 9 are secured to the cover on the inside thereof and serve as retaining means for sharp pointed articles such as pins, needles and so forth. It will readily be appreciated that cork is a much more efficient material for the purpose mentioned than a pin cushion of the usual construction would be. A retaining strap 10 is secured at its end portion 12 to the inner face of the top of the chest, the central section 15 being spaced from the top to accommodate one or more serving tools, such for example as scissors, etc.

A fixed block 17 is secured in the body part

6 of the chest. This fixed block is formed at its upper surface to accommodate a plurality of cylindrical trunnions and to allow turning movements of said trunnions. Spindles 20 are provided in the chest to hold spools 21 or other articles, and these spindles are secured to the trunnions 18. A block 23 rests on and is secured to the fixed block 17 and is formed to fit over the upper half of the trunnions 18 and to allow turning movements of the latter. Slots 25 are formed in the upper block 23 and the fixed block 17 to allow returning movements upwardly and downwardly of the spindles 20.

The spindles 20 are provided at their free ends with sections 27 pivotally secured thereto by means of pins 28. The sections 27 are normally upturned at right angles to the spindles and function as handles to raise or lower the spindles when it is desired to put spools or other articles on the spindles or to remove the articles therefrom. The handles 27 further serve to retain the spools or other articles on the spindles. The ends of the spindles adjacent the handles 27 are snugly fitted into notches 30 cut in a spindle supporting member 32 which is secured to a side 33 of the body of the chest. The notches or recesses 30 are of such size as to hold the spindles 20 firmly but to allow the spindles to be easily pulled therefrom by a slight force exerted on the handles 27.

What is claimed as new is:

1. In a sewing chest, an article-holding spindle pivotally mounted at one end and pivotally-mounted means secured to said spindle adjacent its other end and functioning as a handle and as means for retaining articles on said spindle.

2. In a sewing chest, an article-holding spindle pivotally mounted at one end and having a pivotally-mounted section at its other end adapted to function as a handle for the spindle and as means for retaining articles on said spindle when turned at an angle thereto and adapted to be turned into alignment with said spindle to allow articles to be placed thereon or taken therefrom.

3. In a sewing chest, an article-holding spindle pivotally mounted at one end and

retainingly but removably held to the chest at the other end and a pivotally mounted section secured to the spindle and serving as a handle and as article-retaining means.

- 6 4. In a sewing chest, a fixed block, a cylindrical trunnion supported by said block and turnable thereon and a spindle secured at one end to said trunnion, said spindle having at its other end a pivotally mounted section to serve as a handle for the spindle and as article-retaining means.

10 In testimony whereof I hereby affix my signature.

JOHN E. MULREY.
